UNITED STATES PATENT OFFICE.

NORMAN McCARTY, OF INDIANAPOLIS, INDIANA, ASSIGNEE TO LYONS-ATLAS COMPANY, OF INDIANAPOLIS, INDIANA, A CORPORATION OF INDIANA.

BREATHER FOR ENGINES.

1,071,328.

Specification of Letters Patent. Patented Aug. 26, 1913.

Application filed May 27, 1912. Serial No. 700,080.

To all whom it may concern:

Be it known that I, NORMAN McCARTY, a citizen of the United States, residing at Indianapolis, in the county of Marion and 5 State of Indiana, have invented a new and useful Breather for Engines, of which the following is a specification.

The operation of the pistons of reciprocating engines having crank chambers produces a continual rise and fall of the air 10 pressure within said crank chambers.

It is the object of my invention to utilize this rise and fall of pressure for the purpose of continuously and noiselessly changing 15 the air in the crank chambers of such engines, thus producing a ventilation having a beneficial cooling effect.

I accomplish this object by the use of a breather. By this breather the heated air 20 in the crank case, when compressed by a stroke of the piston toward the crank case, is allowed to escape noiselessly into the atmosphere, being purified of oil or other fluid before being discharged into the 25 atmosphere. This oil is collected and is drawn back into the crank case by the suction produced by the piston stroke in the opposite direction.

The accompanying drawings illustrate my 30 invention.

In the drawings, Figure 1 is a semi-diagrammatic view of an internal combustion engine having a crank chamber and equipped with my breather; and Fig. 2 is a 35 vertical longitudinal section through the breather.

The engine 10 is of the internal combustion type having a closed but not tight crank chamber 11 the bottom of which 40 forms an oil well 12, the cranks on the engine shaft 13, which carries a fly wheel 14, dipping into the oil in the oil well 12 as the shaft rotates. The oil in the oil well 12 is at about the level indicated. The 45 breather 15 is connected to the crank chamber near the top thereof by a pipe 16, and to the oil well 12 below the oil level therein by a pipe 17, in which is a check valve 18 which opens toward the oil well.

50 The breather 15 comprises an outer casing 20 from the bottom of which the pipe 17 leads. The pipe 16 leads into the casing 20 near the top through an inwardly opening check valve 21, the tension of which may be adjusted by varying the compression of

the spring 22. The cover 23 of the casing 20 has a depending annulus 24 which extends nearly to the bottom of the casing 20, and an upwardly projecting annulus 25 from the top of which a screen 26 in the shape of an inverted cone depends into the annulus 24. An upwardly flaring flange 30 extends from the annulus 25 at an intermediate point in its height, forming between it and such annulus a circular groove 31 which drains into a pocket 32, from which a pipe 33 leads to the pipe 17. While for simplicity of drawing, the pocket 32 and pipe 33 are shown in Fig. 2 as being located on the opposite side of the breather 70 from the pipes 16 and 17, their location may be anything desired. Mounted on the top of flange 30 is a cap 35, the inner surface of which curves inwardly into an annular groove 36 from which a drain pipe 37 leads 75 into the space above a baffle plate 38 supported from the cap 35 over the top of the screen 26. The baffle plate 38 is in the shape of a rather flat inverted cone, and is provided with a drain pipe 39 discharging 80 into the pocket 32. From the top of the cap 35 projects a pipe 40 which discharges the air into the atmosphere.

When the engine 10 is operating, the piston movements vary the pressure of the air 85 within the crank chamber 11. As a piston moves downwardly, the air within such crank chamber is compressed and forced through the pipe 16 and check valve 21 into the casing 20 of the breather 15. The air 90 passes down within such casing around the lower edge of the annulus 24, which serves as a baffle plate and collects some of the oil which the air discharged from the crank case is carrying. This oil drips into the 95 bottom of the casing 20. The air after passing around the bottom edge of the annulus 24 passes up within such annulus, going through the conical screen 26 in such passage. The screen 26 removes more oil from 100 the air, such oil dripping from the lower end of such screen into the bottom of the casing 20. After passing up through the annulus 24, the screen 26, and the annulus 25, the air strikes the conical baffle plate 105 38, and is by it deflected outwardly against the walls of the flange 30 and cap 35, passing along such walls and being discharged thence downwardly into the space above the baffle plate 38. More oil is removed from 110

the air at this time and is collected in the groove 36, whence it drains through the pipe 37 into the cap formed by the baffle plate 38. The air striking the top of the baffle plate 38 is deflected upwardly into the pipe 40, whence it is discharged substantially free from oil into the atmosphere. By reason of the meanderings of the air in its passages through the breather, this discharge 10 is practically noiseless.

The oil from the baffle plate 38 drains through the pipe 39 into the pocket 32, into which also drains the oil collected on the walls of the flange 30 and cap 35. This oil 15 passes from the pocket 32 through the pipe 33 into the pipe 17. When the piston of the engine makes an upstroke, the air in the crank chamber 11 is rarefied. The check valve 21 prevents any air from being drawn 20 back into the crank chamber through the pipe 16. In consequence, the excess pressure within the casing 20 over that within the crank chamber tends to force the oil in the bottom of such casing through the pipe 25 17 and check valve 18 back into the oil well 12. This excess pressure is preferably not sufficient to force any air through the pipe 17, the head of the oil above the pipe 17 being sufficient to over-balance this excess of 30 air pressure in the casing 20. Thus any air which enters the crank chamber is compelled to do so through the various interstices at the joints thereof. This is generally found sufficient to produce the desired cooling ef- 35 feet, and at the same time maintains the average pressure within the crank chamber 11 slightly less than that of the atmosphere. This diminished pressure within the crank chamber is found to be advantageous in as- 40 sisting lubrication, and also in keeping the exterior of the machine free of oil. In case the inward leakage of air through the interstices at the joints of the crank chamber is not sufficient in any case to provide the 45 desired amount of air, an inwardly opening check valve 45 having a rather stiff closing spring may be connected with the crank chamber to admit air to the latter from the atmosphere. Usually, however, such a valve 50 is not necessary.

What I claim as new is:

1. In combination, a reciprocating engine having a crank chamber, a breather connected to the crank chamber to allow the air 55 to escape therefrom when compressed by the piston action, said breather comprising a baffle plate and a strainer for removing oil from the air passing out from the crank case, and a valve for preventing the passage of 60 air through the breather into the crank chamber.

2. In combination, a reciprocating engine having a crank chamber, a breather connected to the crank chamber to allow the air 65 to escape therefrom when compressed by

the piston action, said breather comprising a strainer for removing oil from the air passing out from the crank case, and a valve for preventing the passage of air through the breather into the crank chamber.

3. In combination, a reciprocating engine having a crank chamber, a breather connected to the crank chamber to allow the air to escape therefrom when compressed by the piston action, said breather comprising a baffle plate for removing oil from the air passing out from the crank case, and a valve for preventing the passage of air through the breather into the crank chamber.

4. In combination, a reciprocating engine having a crank chamber, a breather connected to the crank chamber to allow the air to escape therefrom when compressed by the piston action, said breather comprising means for removing oil from such air, and a pipe leading from the bottom of such breather into the bottom of the crank chamber for conducting such oil back to the latter, said pipe being separate from the connection allowing air to escape from the 90 crank chamber through the breather.

5. In combination, a reciprocating engine having a crank chamber, and a breather connected to the crank chamber to allow the air to escape therefrom when compressed by the piston action, said breather comprising means for removing oil from such air, and a pipe leading from the bottom of such breather into the bottom of the crank chamber for conducting such oil back to the latter, said pipe having a check valve which permits flow of oil toward the crank chamber only.

6. In combination, an internal combustion engine having a crank chamber, a breather, a pipe connecting said breather to the upper part of the space within the crank chamber, a check valve for allowing air to pass through such pipe only from the crank chamber to the breather, said breather being provided with means for removing the oil from the air passing through it, and a pipe leading from the bottom of the breather to the bottom of the crank chamber for conducting such oil back to the latter.

7. A breather for producing a change of air within the crank chamber of reciprocating engines, comprising a casing provided with an opening, an inwardly opening check valve controlling such opening, an annular baffle plate within and spaced from such casing and opening into such casing at one end, a tapered screen across the opening through said annular baffle plate, a second casing into which the other end of said annular baffle plate opens, a baffle plate within said second casing and against which air coming from the annular baffle plate strikes, an air discharge pipe leading from said second casing on the other side of the baffle 130

plate therein from the annular baffle plate, and means for collecting the oil which gathers on the various parts.

8. A breather for producing a change of air within the crank chamber of reciprocating engines, comprising a casing provided with an opening, an inwardly opening check valve controlling such opening, an annular baffle plate within and spaced from such casing and opening into such casing at one end, a screen across the opening through said annular baffle plate, a second casing into which the other end of said annular baffle plate opens, a baffle plate within said second casing and against which air coming

from the annular baffle plate strikes, an air discharge pipe leading from said second casing on the other side of the baffle plate therein from the annular baffle plate, and means for collecting the oil which gathers 20 on the various parts.

In witness whereof, I have hereunto set my hand and seal at Indianapolis, Indiana, this thirteenth day of May, A. D. one thousand nine hundred and twelve.

NORMAN McCARTY. [L. S.]
